(57) **CLAIM**

The ornamental design for a hanging accessory organizer, substantially as shown and described.

DESCRIPTION

FIG. 1 is a front perspective view of the hanging accessory organizer, showing our new design;

FIG. 2 is a rear perspective view of the hanging accessory organizer;

FIG. 3 is a front elevation view of the hanging accessory organizer;

FIG. 4 is a rear elevation view of the hanging accessory organizer;

FIG. 5 is a left side elevation view of the hanging accessory organizer;

FIG. 6 is a right side elevation view of the hanging accessory organizer;

FIG. 7 is a top plan view of the hanging accessory organizer; and,

FIG. 8 is a bottom plan view of the hanging accessory organizer.

The broken dash lines shown represent unclaimed subject matter and form no part of the claimed design.

The dot-dash lines shown represent an unclaimed boundary line and form no part of the claimed design.
